United States Patent Office

Des. 191,188
Patented Aug. 22, 1961

191,188

RANGE TOP

Joel A. Del Francia, 912 W. San Marino,
Alhambra, Calif.

Filed Oct. 5, 1959, Ser. No. 57,815

Term of patent 14 years

(Cl. D81—25)

I claim:

The ornamental design for a range top, as shown.
